UNITED STATES PATENT OFFICE.

CHARLES CHISHOLM, OF ST. CLOUD, MINNESOTA.

HOOK AND EYE.

1,391,613.

Specification of Letters Patent. Patented Sept. 20, 1921.

Application filed August 24, 1920. Serial No. 405,566.

To all whom it may concern:

Be it known that I, CHARLES CHISHOLM, a citizen of the United States, residing at St. Cloud, in the county of Stearns and State of Minnesota, have invented new and useful Improvements in Hooks and Eyes, of which the following is a specification.

My present invention has reference to a garment fastener, and is in the nature of a hook and eye.

My object is to construct a fastener of this class in which the coöoperating fastening members may be readily snapped into engagement with each other but which cannot become accidentally disconnected by relative movement of the portions of the garment to which said members are secured.

A further object is to provide a hook member having its free end formed with a laterally extending head, and an eye member having its body portion substantially hook shaped, the upper or jaw portion of the hook having yieldable elements which contact with each other at approximately the central portion of the said jaw, and the outer end of the jaw being depressed to provide a rest for the shank of the hook when the latter has been brought into engagement between the jaw and the body of the eye member.

It is a still further object to provide a garment fastener in the nature of a hook and an eye of a construction whereby the said members, when connected, cannot be disassociated by either a longitudinal or lateral movement by said members, but wherein one of the members must be swung or canted with respect to the other members to permit of the separation of the members.

The foregoing objects may be accomplished by a construction, combination and arrangement of parts, such as is disclosed by the drawings which accompany and form part of this application.

In the drawings:-

Figure 1 is a plan view of a fragment of a garment having the fasteners in accordance with this invention.

Fig. 2 is a sectional view approximately on the line 2-2 of Fig. 1.

Fig. 3 is a view showing the manner in which the hook member must be canted on the eye member to permit of the disassociation of said members.

Fig. 4 is a perspective view of the eye member,

Preferably both of the members of my fastener are formed from a single strand of spring wire. The eye member is broadly indicated by the numeral 1 and the hook member by the numeral 2.

The strand of wire from which the hook 2 is formed has its ends looped, as at 3 to receive the threads which attach the same to the garment. From the eyes extend the shank 4, which is preferably twisted on itself as disclosed by the drawings, and the outer ends of the said shank 4 are bent laterally to provide the head 5. It will thus be noted that the head and shank of the hook 2 are substantially T-shaped.

The eye member 1 has the ends of the strand which constitutes the same looped, as at 6 to receive the threads that secure the said eye to the garment. From the loops 6 the strands are extended toward each other and are twisted upon themselves, as at 6'. From the ends of the twisted portion 6', the strands are diverged outwardly as at 7. The elements above referred to constitute the base or body of the eye. The strands 7, at their outer ends are bent upwardly, as at 8, and are further bent and continued over and substantially in parallelism with the base or body, as indicated by the numeral 9. The strands 9 constitute the outer members of the jaw. The strands 9 terminate a slight distance inward of the eyes 6 of the base or body and have their ends bent inwardly upon themselves, as at 10, 90 continued inwardly in contacting engagement with the strands 9 for a determined distance as indicated by the numeral 11. The portions 11, at approximately the center of the jaw are rounded toward each other, 95 as at 12, and the said rounded portions have their centers disposed in contacting engagement with each other. The rounded portions 12 terminate in straight extensions 13 which are disposed in contacting engagement with the strands 9. The portions 13 have their ends bent downwardly in a line with the upstanding angle portions 8 at the end of the base or body. The numeral 14 designates the arched connecting portion for 100 the downturned ends of the strands 13. The portion 14 provides a rest for the shank 4 of the hook 2, when the hook is engaged in the eye.

In connecting the elements that constitute the fastener the eye 2 is held at a slight inclination with respect to the hook 1, so

that the head 5 thereof will rest upon the base or body of the hook, permitting the shank 4 to be received in the open mouth of the jaw member of the eye. The hook member 5 is moved toward the outer end of the eye, passing between the contacting portion 12 provided by the inner strands 11 and 13. The hook is then turned to bring the same in parallelism with the eye, the lateral head 10 5 being received in the rounded portions 8 between the body and the hook, and the shank 4 being received in the rounded portion 14 of the jaw. A construction, as above described, permits of the members constituting 15 the fastener being easily and quickly associated, but will prevent the accidental disconnection thereof by a relative movement of the portions of the garment to which the members are secured. The members 20 cannot be disconnected by a direct longitudinal movement as the loops 3 of the hook 2 are of a greater width than the depressed portion 14 of the jaw of the eye, and also the said loop members are of a size to 25 contact with the rounded portions 8 of the eye member. Therefore it is necessary to slightly cant the hook to permit of the head thereof sliding on the base of the eye and spreading the contacting portions 12 of the 30 hook in the passage of the shank 4 therebetween before the hook can be disconnected from the eye.

Having thus described the invention, what I claim, is:—

- 35 1. In a garment fastener, a hook including a shank having one of its ends looped and its other end provided with a lateral head, and an eye including a base which has one of its ends looped and formed with a jaw that overlies the base, said jaw having spring 40 contacting members at approximately the center thereof and having an outer depressed portion to receive the shank of the hook when the same has been canted and brought

over the base between the contacting portions 45 of the jaw and arranged in parallelism with the eye.

2. In a garment fastener, a hook constructed from a single strand of wire bent to include a shank having one of its ends 50 formed with loops and its other end formed with a laterally extending head, and an eye for the hook which is also constructed of a single strand of spring wire that has one of its ends bent to provide loops, the strands 55 continuing from the said loops in parallelism for a determined distance and then arranged at an outward angle with respect to each other to constitute the base of the eye, said last mentioned strands are bent upwardly and further bent and continued in parallelism over the base in the direction of the loops to provide the outer or side members of a hook, said last mentioned members being bent upon themselves and 60 extended inwardly in contact with the side members for a predetermined distance and from thence rounded toward each other and the said rounded portions being in contacting engagement and extended to provide 65 straight strands that are disposed in contacting engagement with the outer side members of the hook, said last mentioned strands having their ends bent downwardly opposite the angle end strands of the base, a rounded 70 portion connecting the last mentioned down-turned angle strands, and whereby the hook can be arranged at an inclination to permit of its head traveling over the body of the hook to allow the shank thereof to pass between the contacting members of the jaw 75 and then swung in a line with the eye to have its lateral head contacting between the rounded connection of the base and jaw and its shank resting on the depressed portion at the outer end of the jaw.

In testimony whereof I affix my signature.
CHARLES CHISHOLM.
